UNITED STATES PATENT OFFICE.

ALBERT B. COLTON, OF FRANKLIN, INDIANA, ASSIGNOR OF ONE-HALF TO
ROBERT HAMILTON, OF SAME PLACE.

STUB-AXLE FOR TRUCKS.

SPECIFICATION forming part of Letters Patent No. 289,752, dated December 4, 1883.

Application filed September 15, 1883. (No model.)

To all whom it may concern:

Be it known that I, ALBERT B. COLTON, a citizen of the United States, residing at Franklin, in the county of Johnson and State of Indiana, have invented a new and useful Improved Stub-Axle for Grain-Binder Trucks, of which the following is a specification.

My invention relates to an improvement in stub-axes for forming a bent axle for trucks used to move grain-binders upon from one field to another.

The object of my improvement is to provide a metallic bearing for the wheel which shall be light and strong, and which shall form the offset or bent portion of a bent axle, made by securing two of my stubs to opposite ends of a straight beam or scantling, thereby forming a cheap axle, on which ordinary wagon-wheels taken from the farm-wagon may be put, and form a truck with a low bearing adapted to receive a grain-binder, for the purpose of moving it from place to place.

The accompanying drawings illustrate my invention.

Figure 1 represents a longitudinal section of my stub-axle. Fig. 2 represents a perspective view of a bent axle formed with my improved stub.

A is a casting having a shoulder, b, and a tapering cylindrical portion, c, forming a bearing for the inner end of the hub of a wagon-wheel. (Shown in dotted lines.) A bearing for the outer end of the wheel-hub is formed by a wrought-iron rod, d, having an enlarged cylindrical portion, e, which may be formed integral with rod d, or may be cast thereon. Said rod d is laid in the mold in which casting A is made, in suitable prints formed by the pattern of A, and the metal forming A is cast upon one end of rod d, thereby securing it firmly in position in the center of bearing c. Cast-

ing A is formed also with a short standard, f, and a base, g, having a flat surface, g², and provided with projecting pins h i. A bolt-hole, j, passes centrally through the base and pin h. 45 To form an axle, I take a piece of scantling, C, about three by five inches square, and after cutting it to a suitable length I make recesses in the top, at each end, to receive pins h and i, and bore holes through the scantling at the centers of the recesses for h. I then set a pair of stubs, each formed by a casting, A, and rod b, one on each end of the scantling, and secure each in place by a clip, k, and a bolt, l. 50

A bent axle is thus formed, on which the 55 hind wheels of an ordinary farm-wagon may be used without raising the axle too high to be advantageously used in carrying a grain-binder. The wheels may be retained on their respective bearings by a collar and linchpin, 60 as shown, or by a nut screwed on the end of rod d.

Any suitable bed-frame may be mounted on this axle to receive the grain-binder, or the axle itself may be placed under the heavy portion of the binder, and the forward wheels and axle of the wagon used under the lighter end. 65

I claim as my invention—

1. As a new article of manufacture, the above-described stub-axle, consisting of casting A, having the cylindrical portion C, shoulder b, standard f, and base g, and rod d, having enlarged portion e, all combined in the manner and for the purpose set forth. 70

2. A bent axle formed of a straight timber, 75 having a pair of the above-described stub-axes secured thereto, substantially as and for the purpose set forth.

ALBERT B. COLTON.
